STITCHDOWN LASTING MACHINE

Albert Spatola, New York, N. Y., assignor to
United Shoe Machinery Corporation, Flem-
ington, N. J., a corporation of New Jersey

Application June 23, 1947, Serial No. 756,399

1 Claim. (Cl. 12—7.5)

1

This invention relates to machines for operating upon shoes and is illustrated as embodied in a machine for working end portions and side portions of stitchdown shoe uppers into lasted position and for pressing the outturned lasting margins thereof against projecting margins of soles.

It is to be understood, however, that the invention in certain of its aspects is not limited in its application to machines for use in operating upon stitchdown shoes.

In the manufacture of stitchdown shoes the forming of the toe portions and the lasting of side portions have heretofore been separate and distinct operations performed on two different machines. It is an object of the present invention to provide a single machine for shaping the toes and lasting both side portions of stitchdown shoes, thus eliminating the separate side lasting operation now required, and thereby reducing the manufacturing cost.

It is a further object of the invention to improve the lasting of stitchdown shoes by lasting the toe portion and the entire side portions in a single operation.

With the above objects in view the present invention consists in the provision in a stitchdown lasting machine of a pair of wipers pivotally mounted adjacent to the toe end of a shoe arranged in upright position in the machine, said wipers being constructed and arranged to operate on the toe portion of the shoe and on opposite sides rearwardly to the heel end of the shoe. For supporting the forepart and the shank portion of a sole to be secured to the shoe there is provided a plate having a recess in its upper surface at its heel end. For advancing the shoe towardly relatively to the wipers a shoe upper engaging member constructed and arranged to engage the heel end portion of the shoe is mounted on a slide supported in a recess in the heel end portion of the sole supporting plate. Means herein illustrated as a manually operated screw is provided for advancing the slide.

The invention will now be described with reference to the accompanying drawings and pointed out in the appended claims.

In the drawings,

Fig. 1 is a rear elevation illustrating portions of a stitchdown lasting machine embodying features of the present invention;

Fig. 2 is a side elevation illustrating a heel engaging member operable to urge the shoe towardly into the wipers;

Fig. 3 is a plan view of the mechanism illustrated in Fig. 2;

2

Fig. 4 is a plan view showing the wiper plates in their advanced or closed position;

Fig. 5 is a section taken on the line V—V of Fig. 4; and

Fig. 6 is a plan view of the sole supporting plate, face up.

The machine to which the illustrated mechanism is applied performs a shaping operation upon the toe portion and opposite side portions of a stitchdown shoe upper mounted on a last and arranged in upright position upon a shoe sole S (Fig. 1) mounted on a sole supporting plate 10 (Figs. 1 and 6). The machine performs a lasting operation and thereafter applies upward pressure to the sole supporting plate 10 to bring it into intimate contact with the outwardly flanged lasting margin of the upper. Preferably the contacting surfaces of the upper and the sole are coated with cement to cause them to adhere when the sole is pressed upwardly against the outwardly flanged margin.

While any suitable means may be provided for actuating the illustrated instrumentalities I prefer to incorporate them in a power operated machine for lasting stitchdown shoes. Such a machine is illustrated, for example, in United States Letters Patent No. 1,861,832, granted June 7, 1932, on an application filed in the name of William C. Baxter. The illustrated sole supporting plate 10 is constructed and arranged to be mounted on the block 76 of the Baxter machine in the same manner as the sole supporting plate 78 illustrated therein. In the operation of the Baxter machine upward movement is imparted to the block 76 by power first to move the shoe upwardly into a lasting position determined by its engagement with a holdown or toe clamp 294 and thereafter to apply sole laying pressure to the shoe sole.

Referring to Fig. 4, the illustrated lasting wipers 13 and 14 are provided at their toe ends with notches 16 and 17 to permit them to be mounted upon upwardly projecting studs 17 and 18. Said studs are mounted in wiper carriers which operate to impart to the wiper plates swinging movement about a common axis coinciding with the meeting point of the wiping edges at the toe ends of the wipers. The illustrated wipers extend from the toe end to the heel end portion of the shoe, the heel ends of the wipers being slightly spaced from each other as shown in Fig. 4 when the wipers are in their fully advanced or closed position. The wiper plates have a vertical curvature corresponding to the profile of the shoe bottom and their wiping edges 15a are shaped in accordance with the pattern of the shoe bottom. The

mounting of the wipers on the studs 17 and 18 permits a slight freedom of movement of the wipers relatively to the carriers, such relative movement having its greatest magnitude at the heel end portions of the wipers. In order to permit the operator to manipulate the wipers within the limits afforded by such relative movement of the wipers and the carrier the wipers are provided at their heel end portions with upstanding handles 19 and 20 respectively (Fig. 1) conveniently arranged to be grasped by the two hands of the operator and mounted for swiveling movement on pins (not shown).

In order to urge the shoe towardly into the wiper plates 13 and 14 a resilient rubber member 32 (Figs. 2 and 3) having a generally arcuate horizontal curvature as seen in Fig. 3 is fixed to the head 31 of a yoke 29 pivotally mounted on studs 30 projecting outwardly from a post 24. The vertical position of the member 32 is determined by the engagement of a headed screw 29a (Fig. 3) mounted in the yoke 29 with the post 24, said screw being adjustable to vary the heightwise position of the member 32. A plate 23 is slidably mounted between the parallel side walls of a recess 11 formed in the top of the heel portion of the sole supporting plate 10. For moving the sliding assembly lengthwise of a shoe in the machine a screw 27 is mounted to turn freely in a bore in a boss 25 extending downwardly from the plate 23. Mounted in the plate 23 is a block 26 constituting a half nut which normally engages and cooperates with the left threaded rear end portion of the screw 27. The screw is provided with a crank 28 for convenient manipulation thereof. The rubber member 32 is preferably arranged to engage the back line portion of the upper H (Fig. 1) in a generally central position heightwise of the heel portion of the upper.

Having thus described my invention, what I claim as new and desire to secure by Letters Patent of the United States is:

In a stitchdown lasting machine a pair of wipers pivotally mounted adjacent to the toe end of a shoe arranged in upright position in the machine, said wipers being constructed and arranged to operate on the toe portion of the shoe and on opposite side portions rearwardly to the heel end, a plate for supporting the forepart and the shank portion of a sole to be secured to the shoe, said plate having a recess in its upper surface at its heel end, a slide mounted in said recess and constructed and arranged to support the heel end portion of the sole, a shoe upper engaging member carried by the slide, and means for advancing said slide to bring said member into engagement with the heel end portion of the shoe in the machine thereby to advance the shoe towardly into the wipers.

ALBERT SPATOLA.
